United States Patent Office

Des. 179,347
Patented Dec. 4, 1956

179,347

XYLOPHONE

Grover C. Jenkins, Decatur, Ill., assignor to
G. C. Jenkins Co., Decatur, Ill.

Application February 3, 1955, Serial No. 34,347

Term of patent 3½ years

(Cl. D56—1)

Fig. 2

Fig. 1

Fig. 3

Fig. 4

Figure 1 is a front elevational view of a xylophone showing my new design;

Figure 2 is a top plan view thereof;

Figure 3 is a rear elevational view thereof, and
Figure 4 is an end elevational view thereof.

I claim:

The ornamental design for a xylophone, as shown.
